D. B. HEATH

SHOE TEMPERING MACHINE

Filed May 25, 1926

UNITED STATES PATENT OFFICE.

DONALD B. HEATH, OF WHITMAN, MASSACHUSETTS, ASSIGNOR TO BOSTON ELECTRIC HEATING CORPORATION, OF WHITMAN, MASSACHUSETTS, A CORPORATION OF MASSACHUSETTS.
SHOE-TEMPERING MACHINE.

Application filed May 25, 1926. Serial No. 111,620.

My present invention is a novel and improved tempering machine particularly designed and adapted for tempering the toes of shoes during the process of manufacture. 5 The present invention is an improvement over the construction illustrated and described in my prior Patent No. 1,539,802, issued May 26, 1925, and presents a more efficient structure and results in more satisfactory and efficient work.

An important feature of the present invention is the provision of a heating unit enclosed in a ribbed casing, this casing being positioned in a tank containing a relatively small amount of water. The ribbed construction of the heating unit casing affords a large heating surface with a relatively small amount of water to be transformed to steam, the water in the tank being preferably maintained at a constant level from a supply externally of the tempering machine itself. 15 This permits rapid formation of steam and consequent speedier operation of the machine. The water tank above referred to is fixed to 20 the interior of a chamber or cabinet, the walls of which form the exterior of the machine, this chamber being constructed to act as a chimney for the air therein, which will be heated by the heat of the tank, which consequently effects a rising action of the air, tending to give increased rise to the steam from the interior of the tank. This air space within the chamber also acts as an insulating means between the heating unit and outside of the machine, tending to prevent excessive heat on the exterior of the machine. 25 Further features of the invention comprise a baffle plate or member between the steam generating chamber and the usual tempering chamber, preventing too rapid or sudden rising of the steam in contact with the shoe; additional steam tempering means positioned just underneath the shoe to be tempered; and adjustable shoe holding 30 means to prevent contact of the shoe with the apparatus and position the same relatively with the heating elements to result in the most efficient application of the tempered steam thereto.

40 Further features of the invention, details, novel combinations of parts and advantages, will be hereinafter more fully pointed out and claimed.

Referring to the drawings, illustrating a preferred embodiment of my invention, 55

Fig. 1 is a side section of the machine, partly in elevation;

Fig. 2 is a side elevation of the machine; Fig. 3 is a cross-sectional view on the line 3-3 of Fig. 1;

Fig. 4 is a cross-sectional view on the line 4-4 of Fig. 1; and

Fig. 5 is a sectional detail of the ribbed heating unit casing and baffle plate.

Since the machine illustrated herein is 65 capable of extremely speedy operation, I have herein shown same as constructed to receive a single shoe only, although it will be appreciated that I may vary the size of same to accommodate as many shoes as desired. Since, however, it requires but a relatively short period of time to efficiently temper a shoe by this construction, a machine adapted to hold but a single shoe will serve the purpose equally as well as a multiple 70 machine, and for this reason I have herein illustrated and described a single-shoe machine, but it will be appreciated and understood that I am not limited thereto.

In the machine shown in the drawings, I 80 utilize a cabinet or enclosing casing 1, which may be mounted on a bench, table, or other desirable supporting medium, but I have herein illustrated a preferred form of support, comprising a bracket 4, perforated at 85 5, and by means of which the cabinet 1 may be mounted on a pipe or the like support.

This cabinet 1 is slotted at the rear, as shown at 2, to facilitate insertion of the interior elements of the machine, and also 90 to provide for increased entrance of air to the chamber 3. A tank or steam generating chamber 6 is affixed within and to the cabinet 1 by arms 7 secured to the cabinet by bolts or screws 8. A heating unit, preferably electrical, 9, within a casing 10, is inserted in the tank 6 and held therein by a plate 11 secured to the bottom of the tank by bolts or the like 12. Current conducting wires 13 lead from the terminals 14 to the heating unit 9. Current conducting wires 15 from a suitable source of current are also illustrated. The casing 10 is provided with a plurality of ribs or webs 16, which extend from the casing 10 substantially to the inner wall of the steam gener-

ating chamber. This inner chamber is indicated as 17. The plurality of webs 16, being heated by the unit 9, create a large heat radiating surface in the chamber 17, and since there is a relatively small amount of water contained in the chamber 17 at all times, rapid formation of steam will result. Water is admitted to the chamber 17 through a pipe or connection 18, leading from any suitable source of water supply, which pipe 18 is threaded or attached to a boss 19 on the chamber casing 6. A predetermined water level, here indicated as 20, is maintained in the steam generating chamber 17, this water level being preferably maintained relatively low, for quicker steaming. Upon the formation of steam in the generating chamber 17, the steam will rise upwardly, to the opening 21 in the distributing head 22. A baffle plate 23 is secured to the top of the heater casing 10 by a set screw 24 or the like. The steam must pass this baffle plate around the periphery thereof, the baffle plate being so positioned as to leave a slight annular opening 25 therearound. Once past the baffle plate 23, the steam then enters a chamber or steam chest 26 in the head 22, whence it is distributed, through perforations 27, upwardly between ribs 28, to the shoe 29 to be tempered. The distributing head is secured to the upper arms 30 of the casing 6 by bolts, screws or the like 31. These ribs 28 will also become heated during the operation of the machine, and will have a drying and tempering influence on the steam emerging from the perforations 27. The air in the chamber 3, responding to the action of the heat, will rise, the casing acting as a chimney, and this rising of the air will create a rising action on the steam, in addition to its own rise, thus accelerating the rise of the steam and increasing the efficiency of the machine, and the heated air will also tend to temper the steam before it reaches the shoe being acted upon. If "live" steam were permitted to contact with the shoe, without any tempering of the steam, the leather of the shoe would be burned. The cap 32 of the casing 1, preferably formed integral therewith, is truncated, sloping toward the opening 33 at the top of the machine. This truncated formation of the cap 32 permits any condensation from the steam to run downwardly along the sides thereof and out at the bottom of the machine, without dropping onto the leather of the shoe and marring same. A pair of supporting rods or members 34 are secured to bosses 35 on the cap 32 by set screws or the like, and are pivotable on said bosses. A plurality of cross wires or rods 37 are provided on which the bottom of the shoe 29 rests. An opening or mouth 38 is provided in the cap 32 for the insertion of the shoe

29 to the predetermined extent. The position of the shoe, and the height to which it is raised above the ribs 28, is determined by an adjusting screw 39 threaded through a boss or shoulder 40 on the casing 1. The shoe support is raised or lowered as desired by adjustment of this screw 39.

It will thus be seen that I have devised a novel, extremely efficient and satisfactory operating shoe tempering machine, the operation of which will be readily understood and which is as follows:

The water being constantly in the chamber 17 at the desired predetermined level, such as 20, and current being applied to the heating unit 9, the heating unit casing 10 rapidly heats, radiating heat through its sides and through the webs 16, forming steam in the chamber 17, which steam rises, of its own accord, and due also to the rise of heated air in the interior chamber 3 of the casing 1. The steam passes by the baffle plate 23 into the steam chest or chamber 26 and upwardly through the perforations 27 between the ribs 28. It being desired to temper the forepart of the shoe, such as the toe, box toe and upper materials, the supporting wires or rods 34 and 37 are set to the desired position by adjustment of the screw 39, and the shoe inserted through the mouth 38 into the interior of the cap 32. The shoe is so positioned that it does not touch the webs 28, and the steam is so tempered by the time it reaches the shoe that it will properly temper the leather and materials of same without burning it. A relatively short time only is required for the tempering of each shoe, and the operator can readily reach to the rack and replace the shoe 29 with another, without any loss of time.

It will be appreciated that I may, if desired, form my novel apparatus with means to temper a pair or a plurality of shoes, instead of only one, although the invention is fully embodied in a single shoe tempering machine as well as if applied to a plurality.

While I have necessarily described my present invention somewhat in detail, it will be appreciated that I may vary the size, shape and arrangement of parts within reasonably wide limits without departing from the spirit of the invention as claimed.

My invention is further described and defined in the form of claims as follows:

1. Apparatus of the kind described, comprising an annular cabinet, a steam generating chamber affixed to the interior of said cabinet, means to maintain a predetermined water level in said steam generating chamber, a heating unit contained in a casing in said steam generating chamber, said casing having a plurality of webs for increased heat radiation, a distributing head secured to

- said steam generating chamber, means to limit the volume of steam passing to said distributing head, a plurality of ribs on said head, perforations between said ribs, said cabinet being formed at its uppermost portion as a truncated cone, adjustable shoe supporting means and an opening through which the shoe to be steamed may be inserted into the path of the steam.
- 10 2. Apparatus of the kind described, comprising an annular cabinet, a steam generating chamber affixed to the interior of said cabinet, means to maintain a predetermined water level in said steam generating chamber, a heating unit contained in a casing in said steam generating chamber, said casing having a plurality of webs for increased heat radiation, a distributing head secured to said steam generating chamber, means to limit the volume of steam passing to said distributing head, a plurality of ribs on said head, perforations between said ribs, said cabinet being formed at its uppermost portion as a truncated cone, adjustable shoe supporting means, an opening through which the shoe to be steamed may be inserted into the path of the steam, and means to temper said steam before it contacts with the shoe.
- 15 3. Apparatus of the kind described, comprising an annular cabinet, a steam generating chamber affixed to the interior of said cabinet, means to maintain a predetermined water level in said steam generating chamber, a heating unit contained in a casing in said steam generating chamber, said casing having a plurality of webs for increased heat radiation, a distributing head secured to said steam generating chamber, a baffle plate to limit the volume of steam passing to said distributing head, a plurality of ribs on said head, perforations between said ribs, said cabinet being formed at its uppermost portion as a truncated cone, adjustable shoe supporting means, an opening through which the shoe to be steamed may be inserted into the path of the steam, and means to temper said steam before it contacts with the shoe.
- 20 4. Apparatus of the kind described, comprising an annular cabinet, a steam generating chamber affixed to the interior of said cabinet, means to maintain a predetermined water level in said steam generating chamber, a heating unit contained in a casing in said steam generating chamber, said casing having a plurality of webs for increased heat radiation, a distributing head secured to said steam generating chamber, means to limit the volume of steam passing to said distributing head, a plurality of ribs on said head, perforations between said ribs, said cabinet being formed at its uppermost portion as a truncated cone, adjustable shoe supporting means, an opening through which the shoe to be steamed may be inserted into the path of the steam, and means to temper said steam before it contacts with the shoe.
- 25

In testimony whereof, I have signed my name to this specification.

DONALD B. HEATH.
